CLAIM

The ornamental design of a compact tab lifting tool, as shown and described.

DESCRIPTION

FIG. 1 is a top perspective view of a compact tab lifting tool showing my new design;

FIG. 2 is a bottom plan view thereof;

FIG. 3 is a side elevational view thereof;

FIG. 4 is a front elevational view thereof, the rear elevational view being a mirror image;

FIG. 5 is a top plan view thereof; and,

FIG. 6 is a side elevational view opposite of that shown in FIG. 3;
